UNITED STATES PATENT OFFICE.

JOHN A. LEE, OF BENSON, MINNESOTA.

STORM-SASH HOLDER.

Application filed May 5, 1926. Serial No. 106,864.

This invention relates to a sash holding and fastening device and particularly to such a device which may be used in connection with a window frame and a swinging storm sash secured thereto.

It is the primary object of this invention to provide an improved swinging sash holder which may be readily attached or detached from a window frame and storm sash to securely hold the storm sash in variable positions to prevent rattling of the sash holder and the storm sash.

Another object of the invention is to provide a swinging sash holder for use in connection with storm sashes secured to window frames having the usual window sashes working therein which will not interfere with the operation of the window sashes within the window frame.

20 A more specific object of the invention is to provide a storm sash holder which consists of an arcuate plate which may be pivotally secured to a storm sash, a keeper through which the plate is adapted to work, 25 and means for engaging the plate with the keeper in a plurality of different positions.

Another specific object of the invention is to provide a storm sash holder comprising an arcuate plate having a plurality of 30 notches cut therein on its convex edge and a fixed keeper having an engaging portion adapted to closely engage with the notches in the plate.

These and other objects and advantages 35 of the invention will more fully appear from the following description made in connection with the accompanying drawings, in which like reference characters refer to the same or similar parts throughout the various 40 views, and in which

Fig. 1 is a vertical section through a window frame, having a storm sash connected therewith and showing the device of the invention applied thereto.

45 Fig. 2 is a portion of a transverse section taken on the line 2—2 of Fig. 1, as indicated by the arrows.

Fig. 3 is an enlarged view of a portion of Fig. 1 showing the device of the invention in full lines in one position and in dotted lines in another position and

50 Fig. 4 is a vertical section taken on the line 4—4 of Fig. 3, as indicated by the arrows.

55 In the drawings, a window frame 5 of standard construction is illustrated having

the usual sash stops 6 secured thereto and together with the frame 5 forming slide-ways within which the upper window sash 7 and the lower window sash 8 are adapted 60 to move. A swinging storm sash 9 of standard construction is pivoted to the window frame 5 by any type of two part hinge as the hinge 10, consisting of the portions 10^a and 10^b secured respectively to the window 65 frame 5 and the storm sash 9. Secured to one side of the storm sash 9 preferably adjacent the lower end thereof is the lug 11. An arcuate plate 12 is pivotally secured to lug 11 by means of a pivot 13. A keeper 14 is secured to the outermost stop 6 of the frame 5 preferably by means of screws 15, at approximately the same distance from hinge 10 as the lug 11. Keeper 14 has a body portion 14^a through which the screws 70 75 15 extend, and the angular arms 14^b forming straight notch engaging portions adjacent the body portion 14^a and extending outwardly from the body portion, the ends of said arms opposing each other and being 80 spaced some little distance apart. A detent 16 is secured in the outer stop 6 preferably above the keeper 14. The arcuate plate 12 has a plurality of notches 12^a on its convex 85 edge, and the notch 12^b of greater length than notches 12^a on said edge, adjacent the free end of the plate. The notches 12^a and 12^b extend straight inwardly from the convex edge of the plate, the two sides of each notch being parallel and the distance between the parallel sides of each notch being substantially the same as the width of the notch engaging portion on the lower arm 14^b of the keeper. Notch 12^a is cut so that the portion of the plate 12 from the end of 90 the notch to the top of the free end of the plate will just fit between the ends of the arms 14^b of the keeper. The free end of the plate 12 is reversely bent to form a handle portion 12^c. A notch 12^d is formed adjacent the pivot 13 on the concave edge of the plate. 95

The plate 12 is so formed that the same may be inserted or withdrawn in or from the keeper 14 only by alining the notch 12^b with the opening between the opposing arms 14^b of the keeper and pressing the plate 12 inwardly or outwardly towards or from the adjacent side of the window frame, as the case may be. None of the other notches in 100 the plate are of sufficient length to permit insertion or removal of the plate from the

keeper by alining the same with the opening between the ends of the arms 14^b. The handle portion 12^c will prevent withdrawal of the free end of the plate from the keeper.

5 The individual notches 12^a and 12^b are variably directed so that if plate 12 is positioned so that a notch 12^a or 12^b is placed directly over the notch engaging portion on the lower arm 14^a of the keeper 14, the sides 10 of the so positioned notch will lie in substantial alinement with the sides of the engaging portion of the keeper. When the plate has been brought to such a position in respect to the keeper 14, the plate may be 15 dropped and the notch directly over the notch engaging portion on the keeper will engage with the said portion to securely hold the plate and the storm sash to which the plate is pivoted. Due to the formation 20 of the notches 12^a and 12^b and the notch engaging portion of the keeper, as above described very little relative movement between the plate 12 and the keeper will be possible when such engagement is made and 25 no rattling of the plate and the sash will take place when wind strikes the storm sash. The keeper will also effectually hold the plate 12 so that wind cannot unloosen the plate from the keeper and thereby permit 30 the storm sash to be raised and torn off its hinges.

Preferably each side of the storm sash 9 is provided with one of applicant's sash 35 holders. The window sash 8 having been opened and the arcuate plates 12 at each side of the storm sash 9 having been inserted in their respective keepers, the two plates can be grasped by means of the handle portions 40 12^c and the storm sash 9 moved either inwardly or outwardly. Engagement can then be made between the notch engaging portions of the arms 12^b of the keepers 12, and any of the corresponding notches 12^a or 12^b in the plates. The storm sash can 45 accordingly be securely held in a plurality of positions.

When it is desired to close or fasten the storm sash the plates 12 are again grasped by the handle portions 12^c and the plates are 50 raised and pulled inwardly until the storm sash contacts all the sides of the window frame. The plates 12 are then swung upwardly to the dotted position shown in Fig. 3 and pressed slightly outwardly from the 55 sides of the frame to permit the notches 12^b to be engaged by the detents 16. In this position the notches 12^a will engage with the upper arms 14^b of the keepers 14 to securely lock the sash in closed position. A camming 60 action will take place between the keepers 14 and the plates 12 as the plates are upwardly swung so that the plates 12 will be held by detents 16 under slight resilient pressure. Due to the arcuate shape of the 65 plates 12 the sash may be secured in any po-

sition and yet the guideway for the window sash 8 will not be obstructed by the free ends of the plate.

Applicant's device comprises but few parts, is simply and cheaply constructed and may readily be assembled and placed on any standard type of window frame and storm window. The device is capable of use for securing any type of swinging panel in various adjusted positions. The device has 75 been amply demonstrated in actual practice and has been found to be very successful and efficient for the purposes set forth.

It will, of course, be understood that various changes may be made in form, detail, arrangement and proportions of the parts without departing from the scope of applicant's invention, which generally stated consists in the matter shown and described and set forth in the appended claims.

What is claimed is:

1. A swinging sash holder comprising an arcuate plate adapted to be pivotally secured at one end to the free end of a swinging sash, and a fixed keeper having an engaging portion, said plate having a plurality of spaced straight notches cut in its convex edge, the sides of each individual notch on said plate being cut to extend substantially in alinement with the sides of the engaging portion of said keeper when the sash and plate are swung so that the notch lies over the engaging portion, whereby any one of said notches may be engaged with the keeper to snugly fit the engaging portion thereof, and securely hold the sash from movement in a plurality of positions.

2. In combination with a window frame and a sash pivoted thereto, a device for holding and fastening said sash comprising an arcuate plate pivoted to said sash and having a plurality of notched portions on its convex edge and a notched portion on its concave edge adjacent its pivoted end, a keeper secured to said frame through which said plate is adapted to work and with which the various first mentioned notched portions are adapted to engage to hold the sash in a plurality of positions, a detent secured to said frame whereby when said sash is closed and the free end of said plate is swung toward said sash, the notched portion on the concave edge of said plate will engage with said keeper and lock said sash in said frame and one of said first mentioned notched portions may be engaged with said detent to hold the sash in locked condition.

3. A swinging sash holder comprising an arcuate plate adapted to be pivotally secured at one end to the free end of a sash, said plate having a plurality of spaced notched portions on the convex edge thereof, one of said notched portions being formed adjacent the free end of said plate, a keeper adapted to be fixed in relation to the swinging sash and

having an aperture therethrough within which said plate is adapted to work, said notched portions being adapted to engage with said keeper to hold said sash in various positions, said keeper having an opening in one side thereof, admitting to said aperture, said plate being adapted to be inserted within said aperture only by first alining a notched portion adjacent the free end of said plate with said opening.

4. In combination with a window frame and a sash pivoted thereto, a device for holding and fastening said sash comprising a bracket secured to said sash, an arcuate plate pivoted thereto, said plate having a plurality of notched portions on its convex edge, a notched portion on its concave edge adjacent the pivot, a keeper having a body portion secured to said frame and a pair of angular arms extending from one side of said body portion, the ends of said arms opposing each other and being spaced a short distance apart, the inner edges of said arms and the body portion of said keeper forming a guide way within which said arcuate plate may be inserted from between the opposing ends of said arms, any one of the first mentioned notches being adapted to engage with one of said arms to hold said sash in a desired position, and the notched portion on the concave edge of said plate being adapted to engage with said other arm as said sash is

closed and said plate is swung towards the free end of said sash.

5. The combination with a sash frame and a swinging sash of a swinging sash holder comprising an arcuate plate adapted to be pivoted at one end to the free end of said sash and a fixed keeper adapted to be secured to said sash frame and through which said plate is adapted to run, said keeper having an up-standing parallel-sided straight engaging portion, said plate having a plurality of spaced notched portions on its convex edge, the sides of each notched portion being relatively parallel and the sides of the various notched portions extending in such a direction that as the plate is so positioned in relation to the keeper that any one of said notched portions is placed directly over said straight engaging portion of the keeper, the respective sides of a particular notched portion so situated will lie in planes substantially co-incident with the planes of the respective sides of said straight engaging portion of the keeper, whereby any one of the said notched portions can be snugly engaged with said straight engaging portion to securely hold the sash and said plate from movement in any one of a plurality of positions.

In testimony whereof I affix my signature.

JOHN A LEE.
